UNITED STATES PATENT OFFICE.

WILLIAM E. CRAWFORD, OF CHAPIN, IOWA.

DEVICE FOR HOLDING HAYRACKS.

1,349,496.

Specification of Letters Patent. Patented Aug. 10, 1920.

Application filed August 23, 1919. Serial No. 319,343.

To all whom it may concern:

Be it known that I, WILLIAM E. CRAWFORD, a citizen of the United States, residing at Chapin, in the county of Franklin and State of Iowa, have invented certain new and useful Improvements in Devices for Holding Hayracks; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in attachments to wagons for holding hay racks from sliding back and forth, and consists of a simple and efficient device of this nature which will be herein-after fully described, shown in the accompanying drawings and then specifically defined in the appended claim.

My invention is illustrated in the accompanying drawings which, with the letters of reference marked thereon, form a part of this application, and in which:

Figure 1 is a perspective view of the device of my invention, showing the application thereof to a wagon;

Fig. 2 is a view in end elevation of the device of my invention, the frame member of the wagon on which said device is secured, being shown in section;

Fig. 3 is a detached detail view in perspective of one of the members of my device, and

Fig. 4 is a detached detail view in perspective of one of the braces.

Reference now being had to the details of the drawings by letter:

A designates a plate of malleable iron, or other suitable material, having portions bent parallel to each other and adapted to fit over the side piece B of the frame of a wagon, and D are bolts passing through registering apertures in the plate and in said frame. A bar E is riveted, or otherwise held to the

plate, and has intermediate its ends two spaced upward projecting flanges, formed by doubling portions of the plate upon itself, said flanges receiving between them the rail H of the rack. N are brace brackets which are riveted or otherwise held to the plate, and adapted to bear against the outer faces of the bar which is bent U-shape, thus securely holding the same from lateral bending. Each of said braces is peculiarly formed from a single piece, or blank, of metal. The metal blank, intermediate its ends, is slit transversely from opposite points on the sides thereof, and the metal of said blank from said slit portion to one end of the blank is turned upward on both sides, said upwardly turned flanges being bent against each other. Each brace thus comprises a base portion and a lateral portion in a plane perpendicular to the base and affording a vertical end wall adapted to bear against the adjacent vertical flange of the U-shaped portion of the bar E.

By the provision of a device embodying the features of my invention, it will be noted that the rack may be held from sliding back and forth on the box of the wagon, and so arranged that the rack may be easily and quickly removed and replaced when desired.

What I claim to be new is:

A device for holding hay racks, consisting of a metallic plate having longitudinally extending parallel flanges, adapted to fit against the side piece of a wagon frame, means for securing said plate to the side piece of a wagon frame, a bar disposed upon and extending longitudinally of said plate and having intermediate its ends spaced upward extending flanges, and braces for preventing collapse of said flanges, each of said braces comprising a metallic strip slit transversely intermediate its ends and having upward bent lateral portions, bearing against the outer face of the adjacent flange of the bar.

In testimony whereof I hereunto affix my signature.

WILLIAM E. CRAWFORD.
